UNITED STATES PATENT OFFICE

ADDISON APPLEGATE, OF LIBERTY, NEW YORK

ILLUMINATED DISPLAY DEVICE

Application filed September 30, 1929. Serial No. 396,191.

This invention relates to display devices and with particularity to methods and means for illumination suitable for use in signs or advertising displays.

5 The principal object of the invention is to provide a sign or advertising display device wherein more effective illumination is achieved with a minimum of illuminating units.

10 In achieving the above noted object it is proposed to so dispose the lamps with respect to the sign or member to be illuminated so that there is a minimum of interference with the light and consequent absence of shadow effects on the illuminated surface.

15 Another object of the invention is to provide a sign wherein the surface to be displayed is illuminated substantially entirely by reflected light.

20 Another object of the invention is to provide a sign or advertising display wherein a lamp is so disposed as to uniformly and equally illuminate opposite faces of the display device.

25 A feature of the invention relates to a sign or display device having characteristic displays on opposite faces thereof together with a lamp or lamps disposed within the plane of the display device to reduce shadows or other interference on the surface of the display.

30 Another feature of the invention relates to a sign or display device wherein the characteristic display is formed on a relatively thin sheet member and has opposite faces symmetrically disposed with relation to an illuminating lamp together with means for reflecting the light evenly and equally on opposite faces of the display.

35 A further feature of the invention relates to the method of illuminating a plane surface having characteristic displays on opposite faces thereof by disposing an illuminating lamp in the plane of said surface and reflecting substantially all the light from said device equally on opposite faces of said surface.

40 A further feature relates to an advertising sign or the like wherein the characteristic displays are provided on opposite faces of a thin sheet-like member, said member being disposed within a housing and adapted to be

illuminated substantially without the production of shadows and provided with an adjustable reflector for controlling the quantity of light to be reflected upon said member.

45 A further feature of the invention relates to an advertising sign comprising a relatively thin member carrying with characteristic displays on opposite faces thereof a plurality of lamps symmetrically disposed with relation to said opposite faces, said member and lamps being mounted within a housing having one or more walls thereof adapted to act as reflectors, said walls being adjustable relatively to said lamps and said display member.

50 A further feature relates to the organization and arrangement of elements which go to make up an efficient, economical and readily assembled sign.

55 Other objects and advantages not specifically enumerated will be apparent after a consideration of the following description and the appended claims.

60 While the invention will be disclosed hereinafter as embodied in one particular structure of sign or advertising device it will be understood that the broad features of the invention are not limited thereto and particularly the method of illumination which may be applied to any other type of sign.

65 Accordingly, Figure 1 of the drawings shows a front view in elevation of a sign constructed according to the invention;

70 Fig. 2 is a sectional view of the sign shown in Fig. 1, but taken along the line 2-2 thereof;

75 Fig. 3 is a partial sectional view taken along the line 3-3 of Fig. 2;

80 Fig. 4 shows a modified form of sign wherein the housing members themselves serve as the reflectors;

85 Fig. 5 shows a still further modification applicable to either the embodiment of Fig. 1 or Fig. 4 wherein the light is adapted to be reflected from the bottom of the housing; and

90 Fig. 6 is a detail schematic view showing the manner in which the reflector is adjusted from the exterior of the sign housing.

Referring more particularly to Figs. 1 and 2 of the drawings there is shown a sign housing comprising a base portion 1 to which are attached at opposite ends the upright end walls 2 and 3, respectively. The walls 2 and 3 are joined at their upper ends by means of the longitudinally extending cross-pieces 4 and 5 which may be attached to the end walls by screws, bolts, or other suitable fastening devices. The top of the housing is provided with a V-shaped cover 6 which is adapted to rest upon the cross-pieces 4 and 5 and is adapted to be fastened to the end walls, preferably in a removable manner by means of screws or bolts 7.

The above described housing may be fashioned out of any suitable material, either wood or metal, depending upon the use to which the sign is to be put. The end walls 2 and 3 are provided with respective grooves 8 and 9 and the base 1 is also provided near one edge with a groove 10 adapted to register with grooves 8 and 9 when the housing is assembled. These grooves are for the purpose of receiving and holding the glass window 11.

As will be seen from Fig. 2 a similar set of grooves is provided near the opposite edges of the side walls and the base to receive another glass window 12. While this particular method of securing the glass in position lends itself to easy replacement it will be understood that any other well known manner of holding the glass windows in place may be employed, for example by using brads, putty, or the like. Each of the end walls 2 and 3 and the base 1 are also provided with a similar set of grooves, said grooves being provided in the exact center of the said walls. One of these grooves 13 in the end wall 2 is shown in Fig. 2 of the drawings, it being understood that a similar groove is provided in the opposite end wall and in the base 1. These centrally positioned grooves are for the purpose of receiving and positioning the plate 14 which carries on opposite faces thereof the characteristic displays or advertising matter that is to be illuminated. For purposes hereinafter described it is preferred to make the plate 14 of a thin metal as is consistent with the required rigidity and use to which the sign is to be put.

Positioned within the interior of the housing top 6 is a relatively thin flexible plate 15 which is substantially V-shaped in section, as shown in Fig. 2. This plate 15 is preferably made from metal which has a considerable degree of springiness so that said plate normally rests with the inclined faces thereof resting against the interior wall of the top 6 and with the angle thereof abutting against the corresponding interior angle of the top 6. As shown clearly in Fig. 2 the edges 16 and 17 of plate 15 overhang the upper edge of the

respective glass windows 11 and 12, there being sufficient space between the edges of the windows and the top 15 to enable the inclined faces of plate 15 to be adjusted inwardly and outwardly away from the member 14. For the purpose of effecting this latter adjustment screws 18 and 19 are threaded into the top 15 and have their ends abutting against the inclined faces of member 15. If the top 15 is of wood any ordinary wood screws may be used for this purpose. However, if the top is of metal it may be provided with a suitable threaded hole to receive the screw so that as the screw is turned it changes the size of the angle between the sides of member 15. Thus there is shown in Fig. 6 the member 15 in two different positions, the dotted position representing said member in its innermost adjustment and the full line position representing an intermediate adjusted position for said member.

Fastened to the top 15 by suitable screws or bolts 20 is any well known form of lamp receptacle 21. However, it is to be noted that said receptacle is so mounted as to be symmetrically disposed with relation to the member 14 and that the center line of said receptacle is preferably in the plane of member 14, so that when the lamp 22 is plugged into the receptacle 21 it is in exact alignment with the member 14. In order that the mounting of the receptacle 21 may not interfere with the adjustability of the plate 15 it may be necessary to provide slots in member 15 through which the fastening screws 20 pass. In order that the maximum illumination effects may be produced from the lamp 22 the interior surface of member 15, as well as the interior surface of the walls 2 and 3 of the base 1 are preferably painted with a suitable light reflecting material, such as brilliant white paint or the like. However, it will be understood that the member 15 instead of being painted may be silvered or a metal having a naturally high polish may be employed. With the above described structure it will be seen that since the lamp 22 is positioned directly over the display plate 14 and because the latter is extremely thin the light which reaches the opposite faces of member 14 is substantially all reflected light. Thus, as represented by the dot and dash lines in Fig. 6, the light from lamp 22 strikes equally the opposite faces of plate 14. Furthermore, the light also striking the walls 2 and 3 and the base 1 is likewise reflected to the member 14. It has been found that there is a particular position for the member 15 wherein the maximum reflection effects are obtained and for this purpose the screws 18 and 19 are adjusted until such maximum reflection upon the member 14 occurs. It has also been found that the windows 11 and 12 also act somewhat as reflectors onto the member 14 and that there is an entire absence of any shade.

ows upon the faces of the display member 14. Furthermore, because of the central positioning of the lamps 22 over the member 14 a single lamp is employed for illuminating both the opposite faces of member 14.

Referring to Fig. 4 there is shown another modification of the sign and housing disclosed in Figs. 1 and 2. In this modification the parts which are similar to the embodiments of Figs. 1 and 2 are represented by the same designation numerals. However, it will be noted that the top of the housing instead of being of wood and provided with a separate reflector is made of metal. The metal top is substantially V-shaped and each wall of the top is provided with a section 23 which is swingably attached as by hinges 24 to the central section 25 which is rigidly attached to the end walls in any suitable manner.

The edges 26 of the hinged sections 23 overlie the longitudinally extending strips 27 corresponding to strips 5 of Fig. 1 and the edges 26 are also provided with slots 28 through which pass screws 29 for holding the said hinged sections firmly in adjusted position. In order that the sections 23 may be adjusted to vary the angle of reflection as regards the light from lamp 22 said sections are provided with adjusting screws 18 which have their inner ends abutting against the longitudinal pieces 27. Thus, in order to vary the angle of reflection, all that is necessary is to loosen the screws 29 and to adjust the screws 18 which correspondingly raise or lower the hinged sections 23. The inner surface of sections 23 may be highly polished or may be provided with a suitable light reflecting paint. In the embodiment of Fig. 4 it will also be noted that the lamp or lamps 22 are positioned in exact alignment with the upper edge of the sign display member 14 so that the light is reflected from the inner surface of members 23 equally and uniformly on opposite faces of the sign as herein above described. In order to enable the sign member 14 to be readily removed and replaced the base 1 of the sign housing is provided with a central longitudinal slot which is in alignment with the slots 13 in the end walls.

Pivottally attached to the lower surface of the base 1 are a series of fingers 30 upon which the sign member 14 is adapted to rest. Consequently all that is necessary in order to remove the member 14 is to swing the fingers 30 out of the way and allow the member 14 to drop through the base 1. In this embodiment we notice therefore that the housing cover performs the double function of acting as a reflector and also is capable of adjustment. Furthermore, by means of the hinged sections 23 access is readily gained to the interior of the housing so that the lamps 22 may be easily replaced and other parts of the interior inspected. While there has

been shown one particular structure for enabling the top to be opened to gain access to the interior it will be understood that other equivalent arrangements may be employed. For example, one side alone of the top may be hinged or the hinging may take place along the members 29 without departing from the spirit and scope of the invention.

Referring to Fig. 5 there is shown another embodiment in which the reflector plates are mounted on the base 1. In order that the sign member 14 may rest in the grooved base it may be necessary to provide two separate reflecting plates 31 and 32 which are preferably of spring metal and attached to the base 1 by screws 33. Adjusting screws 34 pass through the base 1 and enable the angle of the reflecting members 31 and 32 to be varied, as herein above described. It will be obvious that the arrangement of Fig. 5 may be used without using the reflectors in the top of the housing. In this case the lamps 22 will be positioned beneath the lower edge of the sign and exactly centrally therewith, as herein above described, so that the light is reflected upwardly from the members 31 and 32 equally on the opposite faces of the sign.

It will also be understood that both reflectors may be used and either a single set of lamps above the top of the sign or below the sign may be employed. Furthermore, the sign member 14 may be provided with cut-out portions wherein the lamps are adapted to be positioned. However, it is found that when the lamps are positioned directly above the upper edge of the sign or directly beneath the lower edge thereof there is a more efficient illumination of the sign and a substantially entire absence of shadow effects.

While specific structures and embodiments are disclosed for carrying out the features of the invention it will be understood that various modifications and changes may be made therein without departing from the spirit and scope of the invention.

What I claim as new and useful and desire to secure by United States Letters Patent is:

1. In a display device the combination of a very thin plate-like member having a characteristic display on the face thereof, a source of light adjacent the edge of said member, and an adjustable flexible sheet-like reflector for said light, said reflector being substantially V-shaped and extending around said edge to reflect the light to opposite faces of said plate-like member.

2. In a display device the combination of an adjustable flexible reflector, a light source, a very thin display plate having the edge facing the light source, and a flexible sheet-like member substantially V-shaped extending around the edge of said display plate.

3. A display device according to claim 2 in which the light source and the display plate are mounted in alignment with the apex of the V-shaped reflector.
  4. A display device according to claim 2 in which said reflector is provided with reflecting members extending on either side of the display plate, said members being adjustable angularly with respect to said plate.
  5. In a display device the combination of a lamp, a thin plate-like display member having an edge facing said lamp, and an adjustable reflector at opposite edges of said member, said reflector being of flexible sheet material.
  6. An illuminated sign comprising a housing, a thin plate-like display member mounted in grooves in the end walls of said housing, a lamp mounted within said housing and in the same plane as that of the display member, and a flexible plate-like reflector attached to the inner surface of the housing top.
  7. A sign according to claim 6 in which the reflector is provided with adjusting devices capable of being adjusted from the exterior of the housing.
  8. A sign according to claim 6 in which the base of the housing is provided with a slit for removal of the display member, and means for supporting said member within the housing when the sign is in use.
  9. A sign comprising a thin sheet-like member carrying displays on opposite faces, means for illuminating said opposite faces equally and uniformly substantially entirely by reflected light, a housing for said member having a removable top, a flexible-sheet-metal reflector, and a lamp secured to said top.
- In testimony whereof I have hereunto set my hand on this 26th day of September, A. D. 1929.
